(Cl. D89—1)

To all whom it may concern:

Be it known that I, Harold W. Darr, a citizen of the United States, residing at Minneapolis, county of Hennepin, and State of Minnesota, have invented a new, original, and ornamental Design for a Combination Food Cutter and Grater, of which the following is a specification, reference being had to the accompanying drawing, forming a part thereof.

Fig. 1 is a view in perspective of a combination food cutter and grater showing my new design;

Fig. 2 is a view in side elevation as seen from the right with respect to Fig. 1;

Fig. 3 is a view in front elevation;

Fig. 4 is a view in rear elevation; and

Fig. 5 is a view in top plan.

I claim:

The ornamental design for a combination food cutter and grater, as shown.

HAROLD W. DARR.
